UNITED STATES PATENT OFFICE.

WALTER DAVIS, OF TULSA, OKLAHOMA.

ROTARY SWITCH.

1,387,361.

Specification of Letters Patent.

Patented Aug. 9, 1921.

Application filed September 20, 1919. Serial No. 325,053.

To all whom it may concern:

Be it known that I, WALTER DAVIS, a citizen of the United States, residing at Tulsa, in the county of Tulsa and State of Oklahoma, have invented new and useful Improvements in Rotary Switches, of which the following is a specification.

This invention relates to a combination switch device and has for its primary object 10 the construction of a combination switch device by means of which an electric circuit may be interrupted in a manner that a person unfamiliar with the combination will be unable to again establish the continuity of 15 the circuit.

An object of the invention is to provide a switch device, the movable elements of which will be silent in their movements and which may be actuated continuously with 20 out any indication that the elements have assumed the required position to close the circuit.

Besides the above, my invention is distinguished in the novel manner of constructing 25 the switch blade so that good electrical connection may be accomplished with a minimum amount of friction.

With these and other objects in view the invention will be better understood from the 30 following detailed description taken in connection with the accompanying drawings, wherein:

Figure 1 is a top plan view of the device.

Fig. 2 is a vertical section of view of one 35 switch.

Fig. 3 is a cross section view.

Fig. 4 is a plan view of complete device.

Again referring to the drawings illustrating one of the many forms in which the invention may be constructed, the numeral 1 40 designates a casing in which is arranged a plurality of switches.

Each switch comprises a base 3 of insulating material having a circular opening 45 4, the circular wall 5 of which has embedded therein a pair of contacts 6 and 7. Attention is called to the fact that the surface of each contact is flush with the circular wall of the opening for a purpose hereinafter set 50 forth.

The numeral 8 designates a rotatable switch blade the end portions of the radially disposed arms of which are recessed, and have arranged therein balls 9 which are 55 forced into engagement with the circular wall by spring 10. Thus it will be seen that spring 10 and contact balls serve in part to

sustain the switch blade in a given contact adjusted position and accomplish that purpose with a minimum amount of friction 60 and silently the balls may be moved into electrical engagement with the contacts. The same effect is accomplished when the balls are moved out of engagement with the contacts. Extending across the base is a pair 65 of spring strips 11 and 12 between which is frictionally gripped a disk 13 carried upon a shaft 14, thus providing a still further means for holding the rotatable switch blade in a given adjusted position. This shaft 14 70 has one end arranged exteriorly of the casing and has secured thereto a button 15. To complete the invention I arrange a dial 16 concentrically of each shaft and co-operating with the pointer 17 on the shaft. 75

Referring to the diagrammatic view it will be noted that the contacts of the switches are relatively displaced so that the position of the various blades must assume when closing the circuit will be different. Knowing 80 the proper combination and watching the movements of the pointers over the dials the various blades can be quickly moved in position to close the circuit. It will be noted that when one of the blades is not properly 85 set the circuit will not be closed although the remaining blades may be in their proper positions.

It is of course to be understood that the invention may be constructed in various 90 other manners than illustrated, and therefore I do not desire to be limited in any manner except as set forth in the claim hereunto appended.

What I claim is:—

A rotary switch comprising a top plate, a cylindrical shell secured upon the underside of said plate, a ring member of insulating material secured within the lower end of said shell, a plurality of contacts embedded 100 within said ring and flush with the wall of the opening therein, a rod journaled through said top plate, a switch arm carried by the lower end of said rod, outwardly sprung-pressed ball contacts in the ends of said arm 105 bearing against the wall of the opening in the ring, a knob on the upper end of the rod, and a pointer on the rod beneath the knob, the top plate being provided with a series of graduations concentric with the rod and 110 traveled over by said pointer.

In testimony whereof I affix my signature.

WALTER DAVIS.
